UNITED STATES PATENT OFFICE.

ULRICH E. ROHDE, OF ROCK RAPIDS, IOWA.

TOWEL-DELIVERY MACHINE.

1,070,536.

Specification of Letters Patent. Patented Aug. 19, 1913.

Application filed December 1, 1911. Serial No. 663,258.

To all whom it may concern:

Be it known that I, ULRICH E. ROHDE, a citizen of the United States, residing at Rock Rapids, in the county of Lyon and State of Iowa, have invented certain new and useful Improvements in Towel-Delivery Machines, of which the following is a specification, reference being had to the accompanying drawings.

10 This invention relates to improvements in machines for delivering towels and like cloths; and an object of this invention is to provide a machine of this character which will be simple in construction, comparatively 15 cheap in manufacture and most efficient, secure and reliable in use.

Another object of this invention is the provision in a machine of this character of suitable guiding devices by which the towels 20 are led to and from the feed mechanism.

A third feature of this invention is the provision in a machine of this character of feed mechanism for presenting a clean towel at and withdrawing the soiled towel from 25 the delivery opening.

A fourth object of this invention is the provision of simple means for disengaging or releasing the soiled towel from the feed mechanism.

30 Other features of this invention will be set forth in the description and claims which hereinafter follow.

In the drawings illustrating the principle of this invention and the best mode now 35 known to me of applying that principle, Figure 1 is a front elevation of my new towel-supplying machine; Fig. 2 is a section on the line A—A of Fig. 1; Fig. 3 is a fragmentary section looking in the direction 40 of the arrow X in Fig. 2; Fig. 4 is a section on the line B—B of Fig. 1; Fig. 5 is a detail showing the feed-disk in plan; Fig. 6 is a detail showing in elevation the feed-disk and its shaft; Fig. 7 is a detail in perspective showing the manner in which the towels 45 are fed to the feed-disk; Fig. 8 is a detail in perspective of the soiled-towel releasing-mechanism; and Fig. 9 is a detail showing the rifle grooves rectified.

50 The machine is inclosed in a suitable cabinet or casing *a* which is provided at its top with a mirror *b* and, below the latter in the order named, with a delivery opening *c* and a coin slot *d* and, near its bottom, with an opening *e* through which projects the free outer end of a foot-operated operating-lever *f* the

inner end of which is suitably pivoted or fulcrumed at *f'* in a bracket *f''* fastened to the inner face of the back wall of the casing and the outer end of which is provided with a suitable pedal *f'''*. Fastened to the front wall of the cabinet within the same, is a series of brackets *g* one of which is at the top and another of which is near the bottom of the casing; and in these brackets is slidably 60 mounted an operating rod *h* the lower end of which is joined at *h'* by a pin-and-slot connection with the foot-lever *f*. The slide-rod *h* is provided with a collar *i* to which is fastened the lower end of a coil-spring *j* the 65 upper end of which is attached to one of the brackets *g*; hence, when the foot-lever *f* is depressed, the spring *j* will be extended; and upon the foot-lever's being relieved of the pressure, the slide-rod *h* will be restored 70 to its original position by the recoil of the spring *j*. Projecting inwardly from the 75 front face of the cabinet is a shelf *k*, which is supported by a pair of braces *m* and which in turn supports the housing *n*. Mounted 80 in a thrust bearing *o* on the shelf *k* is the lower end of a vertically-disposed shaft *p* the upper end of which is supported in a suitable bearing *o'* fastened to the top of the cabinet *a*. Fastened to the vertical shaft 85 *p* is a collar *q* to which is suitably secured, as by rivets, a feed-disk *r* from which projects vertically upward a hollow shaft or sleeve *s* formed with a pair of rifle or helical grooves *t*, *u* which merge into each other at 90 their ends. Slidably mounted upon the sleeve *s* is a ring *v* from which a pin *w* projects inwardly and is arranged to engage the walls of the helical grooves *t*, *u*, when the ring *v* is slid along the sleeve *s*. 95 The ring *v* is carried by the bifurcated end of a forked lever *x* the other end of which is fulcrumed in a bracket *y* fastened to the inside of the cabinet *a* near the top thereof (Figs. 2 and 3). Fastened to the slide-rod *h* is a bracket-arm *z* the other end of 100 which is pivotally fastened to the lever *x*. Hence, when the slide-rod *h* is depressed, the pin *w* is made to travel in one of the helical grooves as *u* and thereby to rotate 105 the feed-disk *r* and its shaft *p*.

The feed-disk *r* is provided with a notch *r'* and is partially surrounded by a band *2* which is a continuation of the outside guide-rail *3* of a pair of helically-disposed guide-rails *3*, *4* and which is prolonged to form one wall *5* of the discharge runway. The upper

end of the other wall 6 of the latter extends under the feed-disk and serves as a finger 6^x to disengage from the notch r' the carrier 7 in which the upper end of the towel is held. 5 This carrier 7 is formed with a ball-shaped head 7' and at its lower end with an eye 7" in which the end of the towel T is thrust. In order to increase the capacity of the feed-runway in which the clean towels are held, 10 the guide-rails 3, 4 constituting this runway are bent into helical form, as is shown in Figs. 2, 3 and 4. Bracket plates n' are fastened to the front wall of the casing within the same and to the band 2 and support the latter. 15 The operation of my new towel machine will be readily understood from the foregoing description, when read in connection with the drawings, and is as follows: Under 20 the influence of gravity, the carriers 7 holding the towels slide down the helically-disposed feed-runway. In the initial position of rest of the feed-disk r, its notch r' registers with the outlet end of the feed-runway 25 and therefore normally holds a carrier 7 bearing a clean towel. A person desiring to operate the machine and thereby obtain a clean towel places his foot upon the pedal f" and presses downwardly the foot-lever f, 30 whereby he pulls down the slide-rod h against the tension of the coil-spring j and forces the ring v downwardly along the sleeve s. The pin w bears against a wall of the groove u and thereby turns the shaft p 35 and the feed-disk r through one-third of a complete turn to carry the clean towel to the delivery opening c. The towel T now hangs between the housing n and the delivery opening c. Holding the foot-lever f depressed with his foot, he uses the towel and, 40 having finished therewith, he relieves the foot-lever of the pressure of his foot, whereupon the coil-spring j recoils, the pin w returns to its original position, passing 45 through the groove t and pressing against a wall of the same, whereby the feed-disk r is carried in the same direction through the remaining two-thirds of a complete turn and comes to rest in its initial position. 50 During the last two-thirds of its turning movement the feed-disk carries with it the towel, which is now a soiled towel and which is disengaged from the notch r' by means of the finger 6^x engaging the carrier 7, which 55 now falls down the discharge runway. Near the end of its fall, the towel T slides down the inclined apron a'. It is to be observed that the soiled towel does not pass over any part of the path of the clean towel.

60 I claim:

1. A towel-delivering machine having a casing formed with a delivery-opening; a feed-runway; a discharge-runway; a housing which is opposed to said delivery-opening and which prevents unauthorized access

to the towels within the casing through said opening; a step-by-step towel-feed device which first carries the towels from the feed-runway into the accessible space between said housing and delivery opening and next, 70 upon being released by the operator, automatically withdraws the towels from said space and delivers them to said discharge-runway; said towel-feed device retaining the towels during their passage from said feed-runway to said discharge-runway. 75

2. A towel-delivering machine having a casing formed with a delivery-opening; a feed-runway; a discharge runway; a step-by-step rotary towel-feed device which is 80 formed with towel-engaging means to pick a towel from said feed runway and which first carries the towel therefrom to said opening and next, upon being released by the operator, automatically withdraws the 85 towel from said opening and delivers the towel to said discharge runway; said towel-feed device holding the towel from its disengagement from said feed-runway to its engagement with said discharge-runway. 90

3. A towel-delivering machine having a feed-runway; a discharge-runway; and a rotary towel-feed device which rotates between said runways and is formed with towel-engaging means that withdraws the 95 towel from said feed-runway; said discharge runway being formed at its inlet end with a towel-guiding device which disengages the towel from said towel-engaging means and guides the towel into said discharge-runway. 100

4. A towel-delivering machine having a feed-runway; a discharge-runway; and a rotary towel-feed device which rotates between said runways and is formed with 105 towel-engaging means that withdraws the towel from said feed-runway; said discharge-runway at its inlet end being shaped to form a cam-like finger which disengages the towel from said towel-engaging means 110 and guides the towel into said discharge-runway.

5. A towel-delivering machine having a feed-runway; a discharge-runway; a wheel-like rotary towel-feed device formed with 115 towel-engaging means that withdraws the towel from said feed-runway and delivers it to said discharge-runway; a shaft upon which is mounted said towel-feed device; and cam-controlled mechanism which turns 120 said shaft and thereby rotates said towel-feed device between said runways.

6. A towel-delivering machine having a horizontally-disposed towel-feed device; a vertically-disposed shaft which carries said 125 device and which is formed with a cam groove; an actuating device arranged to slide up and down on said shaft and to engage the walls of said groove; and means for moving said actuating device up and 130

down upon said shaft to swing said towel-feed device.

7. A towel-delivering machine having a feed-runway; a discharge-runway; a wheel-like rotary towel-feed device which is formed with towel-engaging means that withdraws the towel from said feed-runway and delivers it to said discharge-runway; a shaft upon which said towel-feed device is mounted; and cam-controlled mechanism which turns said shaft in a single direction and thereby rotates said towel-feed device to carry the towels from said feed-runway to said discharge-runway.

15 8. A towel-delivering machine having towel-feed mechanism formed with a pair of cam grooves which communicate with each other; and means which engage the walls of the latter in succession and are arranged to be operated by the customer to move the towel - feed mechanism step-by-step.

20 9. A towel-delivering machine having towel-feed mechanism formed with a pair

of cam grooves which communicate with each other at their ends; and means which travel from one of said grooves to the other and are arranged to be operated by the customer to move the towel-feed mechanism step-by-step.

30 10. A towel-delivering machine having towel-feed mechanism arranged to turn and formed with a pair of cam grooves; a slide which travels in the latter and engages the walls thereof; mechanism which is arranged to be actuated by the customer and which moves said slide through one of said grooves to feed a towel; and an automatic device which moves said slide through the other of said grooves and restores said mechanism to its initial position.

Signed at said Rock Rapids, this 25th day of November, A. D., 1911, in the presence of the two undersigned witnesses.
